UNITED STATES PATENT OFFICE.

EDWARD E. CLAUSSEN, OF HARTFORD, CONNECTICUT.

DISPENSING APPARATUS.

1,083,727.

Specification of Letters Patent. Patented Jan. 6, 1914.

Application filed April 18, 1912. Serial No. 691,742.

To all whom it may concern:

Be it known that I, EDWARD E. CLAUSSEN, a citizen of the United States, residing at Hartford, in the county of Hartford and State of Connecticut, have invented certain new and useful Improvements in Dispensing Apparatus, of which the following is a specification.

This invention relates to dispensing apparatus, among the objects of the invention being the provision of a simple and effective article of this character which can be inexpensively and readily made and which may be employed with advantage for receiving and delivering articles of various kinds, although the same is shown in the drawings accompanying and forming part of the present specification, as organized for containing and supplying paper drinking cups which are usually but not necessarily, arranged in nested order in the form of a vertically-disposed stack. In the construction shown the dispensing means is coin-controlled, although in some cases the coin controlled means may be omitted.

In said drawings I represent in detail one of the several convenient forms of embodiment of the invention which to enable those skilled in the art to practice the same will be set forth fully in the following description, while the novelty of the invention will be included in the claims succeeding said description, from which it will be clear that I do not limit myself to such disclosure; I may depart therefrom in several respects within the scope of the invention covered in said claims.

Referring to said drawings: Figure 1 is a front elevation of the lower portion of an apparatus involving my invention and showing the cover or front plate of the casing removed. Fig. 2 is a vertical sectional view of the same, the section being taken from front to rear thereof. Fig. 3 is a horizontal section on the line 3—3 of Fig. 2 in the direction of the arrow, and, Fig. 4 is an inside face view of coin-controlled mechanism and also shows in section a portion of a dispensing member.

Like characters refer to like parts throughout the several figures of the drawings.

As intimated apparatus involving my invention may be employed with utility for dispensing articles of various kinds, and it preferably includes a container in which certain of the operative parts and also the arti-

cles to be dispensed are inclosed. In the present instance this container consists of a casing or box as 5 and a tube as 6 rising therefrom, the former being generally made of sheet metal and the latter of glass as common in this art, and as illustrated for example in Letters Patent No. 1,010,861 granted to me December 5, 1911. The tube 6 is primarily adapted to contain the articles to be vended and in the case of drinking cups, such cups are arranged in nested order in the tube 6, the lower portion of the stack extending into the box or casing 5 through a hole 7 in the top thereof as shown best in Fig. 2.

As will hereinafter appear means are provided for sustaining the stack of cups and for also effecting the removal of the lowermost cup from the stack, and when said lowermost cup is thus removed, it may as illustrated pass by gravity into a delivery member which is shown consisting of a chute 8 of approximately tubular form, the upper end or mouth of which is below and practically coincident with the hole 7. As a matter of fact the lowermost cup of the stack is normally within the upper portion of the said chute. The latter is shown as being at a slant or at a forward downward inclination and as having a hand hole 9 in its forward side. When the lowermost cup is separated from the stack, it falls into the chute 8 and passes down the same onto the bottom 10 of said chute which constitutes a temporary support for the cup, and the hand can be passed through the opening 9 to obtain the cup on the shelf or support 10, the hole 9 being made sufficiently large to permit the free passage therethrough of a cup.

I provide means as will now appear, for supporting the stack and for also removing a cup from the stack, and these means form part of a movably mounted member which may as shown, consist of a slide such as that denoted in a general way by 11 and which in the construction illustrated has a movement in the casing or box 5 from front to rear thereof, the side walls of said box interiorly thereof having parallel ways 12 for receiving and guiding the slide 11 in its back and forth movement. As shown the slide is of skeleton or open construction so as to provide for the projection therethrough of the lower portion of the stack of cups. The side bars of the slide 11 are shown provided with inwardly extending complementary flanges 13,

the inner edges of which normally support the stack, the outwardly extending bead, rim or equivalent portion of the lowermost cup, overlying the inner side portions of 5 these two flanges or stack supporting members 13. Forward of these flanges 13 and slightly spaced therefrom are practically duplicate flanges 14 constituting auxiliary stack-supporting means and which are 10 adapted to also support the stack during or at about the time the lowermost cup is being removed or withdrawn. The slide 11 is preferably positively held in its normal or forward position, and for this purpose 15 spring means may be provided, there being two springs 15 shown for this purpose, the rear ends of said springs being connected with the downwardly-extending rear flange 16 of the slide 11, while the forward ends 20 thereof are connected to pins 17 within the casing or box 5 at or near the forward portion thereof. When the slide 11 is moved rearwardly to effect the removal of a cup, these springs are stretched, so that when the 25 slide is freed the springs can instantly return said slide to the primary position thereof. The flanges 14 are upwardly and inwardly inclined, and their high portions or edges constitute the effective parts thereof. 30 As already intimated when the slide 11 is in its forward position the lowermost cup will have its outwardly flared portion resting on the two flanges 13 to thus support the stack. To free the lowermost cup from the supporting effect of the two flanges 13, the slide 11 is moved rearward and immediately after the flanges 13 pass from under the lowermost cup, the active portions of the flanges 14 will engage the second lowermost cup and 35 practically at the same time the lowermost cup will be positively removed from the stack which at this point is sustained by the flanges 14, the two sets of flanges as will be clear, operating so far as their active portions are concerned, in superposed planes. The flanges 14 are in turn flanged as at 18, the flanges 18 depending from the flanges 14 and as will now appear constituting cup removing members being for this purpose, made in the form 40 of cams, and their lower edges being upon a slight downward forward curve. The rear ends of these cams or flanges 18 are practically pointed or of wedge shape. Therefore, just after the flanges 13 pass free of the lowermost cup, the entering ends of the cams 45 will engage over the top of said lowermost cup and as the slide 11 continues to move rearward, said flanges will sweep across the top of the lowermost cup and thereby force 50 the same away from the stack, and when the said cup is wholly separated from the stack it will fall into the chute 8 and be disposed of in the manner already described. The forward ends of the two cam flanges 18 are 55 bent toward each other on inward curves so

as to properly engage over the top of the cup, said top being as will be clear of circular formation.

Depending from the wall of the opening 7 is a lug or ear 19 which engages the lower part of the stack of cups to keep same from being moved forwardly. There are diametrically opposite lugs as 20 also depending from the wall of said opening 7 and the lugs 19 and 20 with a lug 21 receive and steady the 75 lower portion of the stack. The lug 21 also acts as a stop lug to prevent the cup separated from the stack being carried rearward with the slide 11, the rear crossbar 16 of the slide 11 being notched as at 22 for the passage of the said lug 21 as the slide 11 moves backward and forward.

As already intimated, the apparatus involves coin-controlled means, and although said means may vary decidedly as to character that shown and now to be described answers satisfactorily, said coin controlled means in the construction shown operating in connection with the slide 11 or some equivalent thereof. The different parts of 90 the coin controlled mechanism are supported in an auxiliary casing or shell 23 open on its inner side and fastened by screws as 24 or otherwise to one side of the main casing 5. The slide 11 is shown provided with a lateral extension 25 terminating in a head 26 of substantially circular or disk form, located in the shell or casing 23, the adjacent side wall of the main casing 5 having an opening or slot 27 through which said extension or arm 25 projects, said arm or extension 25 moving longitudinally of said slot 27 during the reciprocation of the slide 11. It will be clear that when the arm or extension 25 is operated, the slide 11 will be 100 operated a similar extent. This arm 25 cooperates with a manually operable member accessible exteriorly of the apparatus, and in the present instance a coin is utilized as a means for practically coupling said manually-operable member and said arm or extension; that is to say when a coin or its equivalent is not properly placed, the manually operable member can be actuated without effecting anything, but when a coin or 110 its equivalent is properly placed, it serves as a means for operatively-associating the two parts, so that when the manually-operable member is actuated, the slide through said coin will be likewise actuated, to effect 120 the removal of a cup from the stack in the container. A manually-operable member such as answers my purposes is the slide 28, which as shown consists of a practically flat plate supported for sliding movement in a 125 substantially-horizontal direction against the outer wall of the auxiliary casing 23, said wall and top of the casing having bent plates 29 and 30 for supporting and guiding the slide 28 which latter is shown equipped 130

with a lateral projection 31 terminating in a knob or equivalent operating member 32, the outer wall of the casing 23 being slotted as at 23' to receive and permit the movement of, the said projection 31. In the construction shown the slide 28 is provided on its inner side with the approximately L-shaped arm 33, the head 26 having a slot 34 extending approximately radially thereof from the upper edge to about the center thereof, said slot being sufficiently wide to freely receive the free or downwardly extending branch of the arm 33, so that if a coin be not introduced and the slide 28 be moved rearward the free or downwardly-extending branch of the arm 33 on the rearward movement of the slide 28 will pass through said slot 34 without accomplishing anything. The plate 30 to which I have already referred is provided with a lateral flange 35 constituting a temporary rest for the coin which is introduced into the machine through the slot 36 in the top of the casing 23, said slot being so positioned that on the introduction of a coin, it will fall onto the rest or support 35 and be in the path of movement of the free branch of the arm 33 and in front of the disk-like head 26. It will be assumed that a coin is passed through the slot and that it is sustained upon the rest or shelf 35 between the arm 33 and the head 26 and that the parts are in their normal positions. Therefore, when the slide 28 is moved rearward through the operation of the knob or finger-piece 32, the coin will be pressed by the arm 33 against the head 26 whereby the slide 11 through the interposed coin, can be moved rearward to an extent sufficient to effect the removal of a cup in the manner already described. The slide 28 is shown having at its inner or rear end the inwardly-extending ear 37 against which one end of the coiled spring 38 bears, the opposite end of said spring bearing against the rear wall of the auxiliary casing 23. When the slide is moved rearward in the manner indicated, this spring is compressed, so that when the hand is disengaged from the knob 32, the spring 38 will return the slide 28 to its original position. The terminal portions of the spring 38 encircle pins as 39 on the lug 37 and casing 23 respectively, which provide a simple means for holding said spring in place. Fastened to the top of the auxiliary casing 23 is a plate 40 having near its forward portion in the under side the cam surface 41, and this plate or cam as the head 26 moves rearward is adapted to extend through the slot or notch 34, so that the cam face 41 will thereby move the coin downward, for a reason that will now appear.

A yieldable detent or stop such as the spring 42 is shown, the shank or butt of said spring being fastened to the rest or shelf

35, the inner portion of which is curved downward as at 43 to conform approximately to the curve of the cam face 41. As the head 26 and slide 28 are moved forward in the direction indicated carrying with and between them the coin, said coin will travel along the spring 43, and owing to the cam face 41 said coin will be lowered thereby bending or flexing the spring 42 and the instant that the coin passes out of contact with the spring, the latter resumes its original position and in doing so moves to the front of the coin, and hence when any attempt is made to withdraw the parts the coin will be positively dislodged, so that "beating" of the machine by moving the slide 31 back and forth is not possible.

The casing 23 is provided with a guard 45 which covers the forward portion of the slot 23' whereby when the slide 28 is moved rearward, a knife or the like cannot be passed through said slot to effect the removal of the cups.

What I claim is:

1. A dispensing apparatus comprising a container for a stack of nested drinking cups, and a slidable member provided with primary and secondary supporting means, the primary supporting means being adapted to support the stack when said member is in normal position and the secondary supporting means being adapted to support the stack at a higher point when said slidable member is shifted, said slidable member being provided with means for positively removing a lower cup approximately at the time the stack is freed by said primary supporting means.

2. A dispensing apparatus comprising a container for a stack of nested drinking cups, and a slidable member provided with primary and secondary supporting means, the primary supporting means being adapted to support the stack when said member is in normal position, and the secondary supporting means being adapted to support the stack at a higher point when said slidable member is shifted, said slidable member being provided with cup removing means active when the stack has been freed by said primary supporting means.

3. A dispensing apparatus comprising a container for a stack of nested drinking cups, and a slide provided with primary and secondary supporting means, the primary supporting means being adapted to support the stack when said slide is in normal position and the secondary supporting means being adapted to support the slide at a higher point when said slide is shifted, said slide having cup removing means active when the stack is freed by said primary supporting means.

4. A dispensing apparatus comprising a container for a stack of nested drinking

cups, and a slide provided with primary and secondary supporting means, the primary supporting means being adapted to support the stack when said slide is in normal position and the secondary supporting means being adapted to support the slide at a higher point when said slide is shifted, said slide having cam cup removing means active when the stack is freed by said primary supporting means.

5. A dispensing apparatus comprising a container for a stack of nested drinking cups, and a slide provided with two sets of flanges, the active portions of which are in 15 superposed planes, one set of flanges constituting primary supporting means and the other set of flanges constituting secondary supporting means, the primary supporting means being adapted to support the stack 20 when said slide is in normal position, and the secondary supporting means being

adapted to support the stack at a higher point when the slide is shifted, the flanges which constitute the secondary supporting means being provided with cams for withdrawing the lowermost cup on the movement of the slide after the stack has been released by the primary supporting means.

6. In a vending machine, the combination of means for supporting a stack of drinking cups, and a spring retracted slide provided with an opening through which the stack extends and also provided with means for positively separating the lowermost portion of the stack from the remainder thereof on the forward movement of said slide.

In testimony whereof I affix my signature in presence of two witnesses.

EDWARD E. CLAUSSEN.

Witnesses:

HEATH SUTHERLAND,
L. L. MARKEL.
